UNITED STATES PATENT OFFICE

2,608,155

PRINTING MACHINE FOR SHOW CARDS

Arthur H. Kohlbusch, Grayslake, Ill., assignor to
Showcard Machine Co., Chicago, Ill., a corpora-
tion of Illinois

Application April 8, 1948, Serial No. 19,836

1 Claim. (Cl. 101—269)

1

This invention relates to a printing machine for show cards, and the like. It is particularly adaptable for printing advertising cards, show cards, and a variety of cards containing other type of information.

An object of the invention is to provide an improved printing machine for cards, and the like, in which the working parts are assembled for quicker action, more accurate printing, and for longer life. Yet another object is to provide means for protecting the roller employed, for bracing and locking together the manually-operated parts, for providing better supports for the type blocks and more effective means for securing the cards to be printed upon the device. Other specific objects and advantages will appear as the specification proceeds.

The invention is illustrated, in a specific embodiment, by the accompanying drawing, in which—

Figure 1 is a broken vertical sectional view of apparatus embodying my invention; Fig. 2, a transverse sectional view; Fig. 3, an enlarged broken perspective view of the card-gripping mechanism shown; Fig. 4, a perspective assembly view of the improved clamp structure; Fig. 5, a broken view in elevation of the clamp shown in position upon the type-supporting bar; and Fig. 6, a perspective view of a portion of the type-supporting bar.

In the illustration given, 10 designates a frame having its ends equipped with depending supports 11. The supports 11 provide a longitudinal space below the main beam portion of the frame. Carried by the frame 10 is a bed plate 12. A rack 13 extends longitudinally of the frame along each side thereof, while a rack 14 extends along each end of the plate. A type-supporting bar 15 is provided with a notched or cut-away end portion 16 adapted to extend into the notches 17 of oppositely-disposed racks 13 or 14. In the illustration given in Figs. 1 and 2, the bar 15 extends transversely of the plate 12 and engages the longitudinal racks 13.

Mounted upon the type-supporting bar 15 are the type members 18, which are preferably formed in the block-like shapes illustrated, having spaced leg portions 19 which straddle the type-supporting bar 15. The slot thus formed by the legs 19, as shown best in Fig. 1, is accurately formed to fit tightly upon the bar 15 so as to provide the necessary straight and accurate lines of type in the final printing operation. The type blocks 18 are provided, at their tops, with type configurations 20 in the form of letters, char-

acters, pictures, or portions thereof, as required for the printing operation.

In order to lock the type bodies 18 accurately in position upon the type-supporting bar 15, I provide the following structure: The type bar 15 is, preferably, equipped with the saw-like notches 21, as shown more clearly in Figs. 2, 5 and 6. Receiving the bar 15 is a clamp member 22, which may be formed of a sheet metal strip, as shown more clearly in Fig. 4. The member 22 is provided with a lower rectangular portion 23 snugly receiving the bar 15. The upper portion 24 is coiled to receive the compression spring 25. The member 22 is characterized by having an inwardly-turned neck portion 26, which extends in a flat plane almost across the top of the rectangular portion 23. This flat wall or neck 26 is extremely important in the locking operation illustrated in Fig. 5, in that the flat wall 26 provides a wide engagement with the notch 21 of the bar 15, and thus anchors the spring 25 firmly against tilting in the supporting of the type 18.

In order to support the board 27, which is to be printed, well above the type 18 prior to the final printing step, I provide the spacer blocks 28 which are similar to the type members 18 but which are equipped, at their tops, with short spring members 29 effective for holding the board 27 out of contact with the type prior to the final printing step, as shown more clearly in Fig. 1.

The frame 10 is equipped, on each side thereof, with a track portion 30. On either side of the frame is an end plate 31. The end plate carries on its lower side a pair of ball bearing-equipped rollers 32, which bear against the underside of the track flange 30. The end plates 31 are provided with ball bearings 33 receiving a roller shaft 34, and the shaft 34 is provided, at each end, with a rigid roller 35 of steel, or other suitable material, resting upon the upper portion of the track 30. Extending between the rollers 35 on shaft 34 is an impression roller 36, which may be resilient or provided with a resilient outer surface. The resilient roller 36 is protected by the rigid rollers 35, which roll upon the track 30.

Securing the bottom ends of the end plates 31 is a cross rod 37. Securing the top portions of the end plates 31 is a tube 38, which also provides a handle for operating the structure.

At one end of the frame, there is provided a beam 39 having a curved end portion 40, as shown more clearly in Fig. 3. A bar 41 is provided with a rounded end 42 supported for rotation in the curved end 40 of member 39. A coil spring 43 has one end anchored within a recess in bar 41 and

another end anchored within the curved end 40, as shown more clearly in Fig. 3. The spring serves to maintain the bar 41 normally in the position shown in Fig. 3. The bar 41 may be equipped with a handle 44 for operating the same. The bar 41 may also be provided with a clamping bar 45 extending forwardly and provided with a downwardly-turned edge 46 adapted to engage one end of the card 27. The bar 41 is preferably provided with a series of spaced clamping bars 45 for locking one end of the show card upon the supporting member 39, as shown more clearly in Fig. 1.

Operation

In the operation of the device, the card 27 is placed in position, as illustrated in Fig. 1. Preferably, the handle 44 is rocked downwardly to lift the clamping bars 45 until the card 27 is in place. The handle is then released to allow the bars 45 to grip the card at one end, as shown in Fig. 1. It will be understood that the type has previously been inked by passing an inking roller, etc. over the type. The card 27 is prevented from meeting the type by the supporting springs 29. The handle 38 is then grasped and pressed forwardly to draw the roller 36 over the card 27. The card is pressed down against the force of spring 29 and into contact with the type. The handle 44 may be then swung downwardly after the roller is removed from contact with the card to release the card and to permit it to be withdrawn. The printing operation may, if desired, be from either end of the machine.

In the arrangement of the type 18, the desired number of type members 18 may be placed upon the type supporting bar 15, and then locked securely in a group by the clamps 22, as shown more clearly in Figs. 2 and 5. By providing inclined teeth about the notches 24 and by providing a transverse or flat neck 26 on the members 22, it is possible to obtain a graduated adjustment of pressure since the members 22 may be pressed downwardly or upwardly within the inclined walls forming the notch 21 of bar 15 for exerting the desired pressure.

While, in the foregoing specification, I have set forth one specific structure in considerable detail for the purpose of illustrating one embodiment of the invention, it will be understood that such details of structure may be varied widely by those skilled in the art without departing from the spirit of my invention.

5 I claim:

In a printing machine for show cards and the like wherein the type members face upwardly in horizontal alignment, the improvement consisting of a type holder structure, comprising a type-supporting bar having the top thereof provided with a series of meeting notches with inwardly and downwardly inclined sides, at least one type member movably mounted on the top of said bar, and clamping members tiltably mounted on said bar on each side of said type members by means of a ring structure enclosing said bar, said clamping members having upwardly extending arms equipped with inwardly extending compression springs attached thereto and engaging the outer type members so that movement of said clamping members along said bar adjusts the clamping pressure exerted on said type members by said springs, said ring structure providing a transverse upper neck extending substantially the width of the sides of said notches seatable at various inclinations on the notched top surface of said bar being maintained in a selected position by engagement with an inclined side of one of said notches, whereby any desired pressure can be applied to hold said type members in correctly spaced relation.

ARTHUR H. KOHLBUSCH.
